ALFRED SYDNEY BEAVON, OF GLASGOW, SCOTLAND.

APPARATUS FOR CARBURETING AIR.

Application filed August 14, 1922. Serial No. 581,904.

To all whom it may concern:

Be it known that I, ALFRED SYDNEY BEAVON, 149 Hill Street, Garnethill, Glasgow, Scotland, a subject of the King of Great Britain, have invented certain new and useful Improvements in and Connected with Apparatus for Carbureting Air, of which the following is a specification.

This invention is directed to apparatus for carbureting air involving broadly the use of a mixing and carbureting valve, through which air is drawn and to which gasoline is delivered in regulatable quantities, with which valve is combined a pump serving to draw the air and gasoline in mixed and carburetted condition through the valve, and to further carburet the air through forcing the same through a body of gasoline within the pump structure, the carburetted air being finally delivered to a gas holder which automatically controls the open and closed positions of the valve.

In order that the invention may be more clearly understood, reference is made to the accompanying drawings which show one construction of apparatus by way of example:

Fig. 1 is a part sectional view of the apparatus.

Fig. 2 is a part sectional view of the pump casing and of the rotary drum and of the valve.

Fig. 3 is a sectional view of the volatile fuel feeding means.

Referring more particularly to Figs. 1 and 2, a volatile fuel container 1 is closed by a cover 2, provided with an air hole 2^a, and is securely fastened to the casing of a rotary pump 3, and volatile fuel is supplied to the container through the pipe 4. A shaft 6 is rotatably mounted in the container 1, and a cam 5 is secured to the end which projects into the container, a handle 7 being secured to the outer end. The handle 7 is provided with a pin 8 adapted to engage in holes 9 formed in the quadrant 10, arranged on the side of the container 1, (or it may be provided with an opening adapted to engage pins secured in the quadrant) whereby the lever is adapted to be set in a number of different positions and to move the cam 5 as required. The buckets 11 are provided with lips 12 and are pivotally mounted on pins 13 which are secured to the ends of a spider 14, fixed to the inner end of a shaft

15 rotatably mounted in the container 1. The buckets are formed or provided with pins, or projections, 16 which serve to engage the cam 5 and to tip the buckets during the rotation of the spider 14. A vessel 17 is formed or provided in the container 1 and is arranged to receive the volatile fuel discharged by the buckets during their rotation. A pipe, 18, is arranged to deliver the volatile fuel from the vessel 17 through an aperture, 20, provided in a cylindrical valve casing 19, (see also Fig. 2) which is, preferably mounted on, and communicates with, the outer casing of the rotary pump 3. A valve 22 is slidably fitted within the valve casing 19, and is preferably of a cylindrical cup-shaped form with two parallel slots 23 in the bottom on either side of a horizontal portion 24, provided with a downwardly projecting stem 25 which is formed with a disc 26 provided with an outer bevelled edge, adapted to co-act with the valve seat 21 to open or close the opening 27 formed therein. The interior of the valve 22 is preferably rounded at the bottom to facilitate the passage of air, which enters therein, to the slots 23. The valve, herein-after termed the carbureting valve, therefore comprises the casing 19, the valve 22, the gasoline inlet 20, the air inlets 23 and the valve seat 26.

The pump 3 comprises a rotary drum 28 which embodies two chambers 71, 72, Fig. 3 separated by a division plate 45 arranged parallel with the end flat walls 73, 74, of the drum. The latter is fixed to a shaft 34, rotatably mounted in the pump casing 29, and is arranged to be rotated by a suitably driven shaft 30, rotatably mounted in brackets secured by bolts 31 to the pump casing. The shaft 30 is extended beyond the supporting bracket and a sprocket 36 is secured thereto and serves to drive the spider shaft 15 in the container 1, by means of an endless chain 37 and sprocket 38 fixed to the shaft 15, simultaneously with the rotation of shaft 34. The chamber 71 in the rotary drum 28 is fitted internally with blades or vanes 39, which extend from the peripheral wall thereof to the centre, and each blade or vane comprises an outer flat portion 41 and an inner curved portion 42. The blades or vanes divide the interior of the chamber containing the same, into compartments 43, each of which is provided with an inlet 44,

2
in the form of a slot or opening in the peripheral wall of the chamber in close proximity to the rear of the blade or vane relatively to the direction of rotation of the 5 drum. Each compartment 43 is also provided with one or more outlets 46, formed in the division plate 45, and close to the concave surface 42 of the blade or vane 39, which communicate with the chamber 72 on 10 the other side of the division plate. An outlet pipe 47 projects upwardly in the chamber 72 from the centre of the drum 28, and is arranged to communicate with a tube 48, connected to a pipe 49 which projects upwardly into a gas holder tank 50.

The gas holder, Fig. 1, comprises a tank 50 and a bell 51, and is adapted to be sealed by liquid contained in the tank 50, and to be guided therein by grooved rollers 52, enclosed 20 gaging pillars 53 secured to the tank 50. A bearing 54 is provided with arms 55 which are supported on the upper ends of the pillars 53, and a rod 56 is slidably fitted therein. The rod 56 is formed at its lower end 25 with a disc 57, and is adapted to be pushed upwards by the contact of the bell 51 with the disc 57 and to be held downwards when the bell is not in engagement with the disc 57 by means of a spring 58, which is accommodated, at its upper end, on the bearing 57 and bears, at its lower end, against a washer 59 secured on the rod 56. The upper end of the rod 56 terminates in a fork, and the end 59a of a cross lever 60 is pivotally 30 mounted on a pin 61 fixed in the rod. The cross lever is pivotally supported on a fulcrum pin 62 fixed in a bracket 63, which is supported at the upper end of the pillar 53. The other end 64 of the lever 60 is provided 35 with a slot 65, and a pin 66, movable therein, is secured to the forked end 67 of a rod 68 projecting downwards, and screwing into the stem 25 of the carbureting valve 22. The gas inlet pipe 40 and an outlet pipe 69 provided in the tank 50 are arranged to project 40 above the level of the water in the tank.

The pump 3 and the gas holder are adapted to be supported by a stand or support 70.

The operation of the apparatus is as follows:—

Volatile fuel is introduced into the container 1 through the inlet pipe 4, and the outer casing 29 of the pump 3 is filled to approximately three fourths of its capacity 55 with fuel.

Before the gas is generated, the bell 51, (Fig. 1) is at its lowest depth in the tank 50, and the spring 58 has moved the rod 56 downwards and, by means of the cross lever 60 fulcrumed on the pin 62 has caused the rod 68 and carbureting valve 22 secured thereon to be moved upwards. The fall of the weight (not shown) causes the drum 30 and shaft 30 to be rotated and by means of 60 the chain sprockets 32, 38 and 33 and chains 65

37 and 35, the spider 14 and the rotary drum 28 of the pump are rotated simultaneously. The buckets 11 (Figs. 1 and 2) are filled with the volatile fuel from the container 1 and, during their upward rotation, 70 the cam 5 engages the projections 16 on the buckets and causes the latter to be tilted to a degree determined by the height of the point of contact of the projections 16 with the curved surface of the cam, which can be 75 made to take place at a higher or lower point, as required, by engaging the pin 8, on the lever 7, with a different hole 9 in the quadrant 10. The buckets discharge the 80 whole or part of their contents into the vessel 85 according to the adjusted position of the cam.

The rotation of the rotary drum 28 causes air to be drawn through the slots 23, in the valve 22, and the volatile fuel from the vessel 17, in the container, 1, is drawn into the valve casing 19, through the pipe, or pipes 18, aperture, or apertures, 20 in a direction at right angles, or thereabouts to the direction of flow of the air into the pump casing, 90 and the air becomes carburetted by contact with the volatile fuel transversing across the slots 23, in the passage formed between the shoulder 22 of the valve and the disc 26. The carburetted air or "air gas" which 95 enters the outer casing 29 of the pump passes through the peripheral openings 44, of the drum 28 into the chambers 43, formed by the vanes or blades 39, and the peripheral openings are sealed by the liquid in the pump casing as the drum continues its rotation. The air gas is compressed by the liquid in the pump under the concave surface 42, of the blades and is gradually forced therefrom as the drum rotates, 100 through the openings 46, in the division plate 45 into the chamber 72 (Fig. 3) and it rises to the surface of the liquid, which was depressed within the compartment to 105 which the gas was admitted, and passes into the outlet pipe 47. After the gas has been discharged from the compartments 43, the latter becomes filled with liquid, until the inlets 44 again rise above the surface of the liquid when it is discharged therefrom. 110 The gas passes through the outlet pipe 47, tube 48, and pipe 49 into the gas holder, and causes the latter to rise in the tank 50, until its upper surface comes into contact 115 with the shoulder 57 on the rod 56, and forces the latter upwards against the pressure of the spring 58. The upward travel of the rod 56 oscillates the cross lever 60 about the fulcrum pin 62, and depresses the end 64 of the cross lever and the rod 66, whereby the bevelled disc 26 on the carbureting valve 22 is forced down upon its seat, and shuts off the supply of "air gas" to the pump 120 3. Means are provided at the junction of 125 the tube 48 and pipe 49 in the gas holder 130

for the removal of any liquid which may collect therein.

It will be apparent from the above description that through proper adjustment of the 5 cam 5, the buckets 11 may be tilted to any degree desired, and hence the quantity of gasoline discharged into the chamber 17 by any one bucket can be regulated accordingly. Obviously, when the valve 22 is 10 open, the suction of the pump 3 will draw in air through the slots 23 and will also draw in gasoline through the pipe 18. If the bucket has delivered a very small quantity of gasoline to the chamber 17, this is 15 all the gasoline that will be admitted through the pipe 18 to the carbureting valve, and whether this amount be several drops or a much larger quantity, it is all that will be delivered under the operation of 20 a single bucket, as under any circumstances the level of gasoline in the chamber 17 will be below the lowest inlet level of the pipe 18 after each discharge of gasoline through the pipe 18. It is obvious that it is the intention 25 to deliver this gasoline to the carbureting valve in such quantities that the larger portion thereof will be taken up by the air, that is, utilized to carbure the air, while the remaining portion, if any, will flow past 30 the valve 22 into the pump 3 to maintain the normal supply therein. Obviously, this regulation can be easily made by causing the buckets to deliver only a predetermined 35 quantity of their contents as they arrive in discharge condition.

What I claim as my invention and desire to secure by Letters Patent is:—

1. In apparatus for carbureting air with a volatile fuel, comprising a container for 40 the fuel, a pump, a gas holder open to the pump, a valve to admit air to the pump, and means to admit volatile fuel in predetermined quantities and at predetermined intervals to the valve to be mixed with the incoming air, to thereby form a mixture of air 45 and fuel for admission through the valve to the pump.

2. An apparatus for carbureting air with a volatile fuel, comprising a container for 50 the volatile fuel, a pump, a gas holder open to the pump, means for supplying the volatile fuel in regulated quantities, and a valve having slots to admit air to the interior of the valve casing and thereafter to the pump, 55 said valve casing having a mixing chamber to receive the regulated quantities of volatile

fuel for the admixture of the air therewith.

3. An apparatus for carbureting air, comprising a container for a volatile fuel, a pump, a gas holder open to the pump, means 60 for supplying the volatile fuel in regulated quantities from the container, a valve to which said volatile fuel in regulated quantities is delivered, said valve also admitting air mixed with said volatile fuel to the 65 pump, and means for automatically controlling the operation of the valve.

4. An apparatus for carbureting air, comprising a container for volatile fuel, a pump, a gas holder open to the pump, means for 70 supplying the volatile fuel in regulated quantities from the container, a valve to which said volatile fuel in regulated quantities is delivered, said valve also admitting air mixed with said volatile fuel to the pump, 75 and valve operating means automatically controlled by the gas holder.

5. An apparatus for carbureting air with a volatile fuel, comprising a container for 80 the fuel, a pump, a gas holder open to the pump, a valve adapted to admit air and fuel to the pump, and means for delivering fuel in regulated quantities to the valve, said means including a spider rotatably mounted in the container, buckets pivotally mounted 85 on the spider and formed with projections, a cam pivotally mounted in the container and adapted to contact with the bucket projections, and means for regulating the height of the point of contact of said cam 90 with the projections.

6. An apparatus for carbureting air with a volatile fuel, comprising a container for 95 the fuel, a pump, a gas holder open to the pump, a valve adapted to admit air and fuel to the pump, and means for delivering fuel in regulated quantities to the valve, said means including a spider rotatably mounted in the container, buckets pivotally mounted on the spider and formed with projections, a cam pivotally mounted in the container 100 and adapted to contact with the bucket projections, and a handle adapted to adjust said cam for regulating a point of contact with the projections. 105

In testimony whereof I affix my signature in presence of two witnesses.

ALFRED SYDNEY BEAVON.
